TRACTIONAL REFUSE OR LIKE CAN

Silvio M. Aitelli, Newark, N. J.

Application December 27, 1941, Serial No. 424,669

2 Claims. (Cl. 280—51)

This invention relates to improvements in refuse cans and like receptacles, such e. g. as ash and garbage cans; and the invention has reference, more particularly, to a tractional type of refuse can or like receptacle.

This invention has for an object to provide a novel construction of tractional can or receptacle having, as a self-contained part of its structure, traction rollers or wheels and novel means for mounting the same in operative disposition relative to the can or receptacle bottom, and in such relation to the can or receptacle as a whole as to assure a low center of gravity thereof with consequent stability thereof when standing at rest.

This invention has for another object to provide a tractional can or receptacle having a bottom structure inclined in plane angular to the perpendicular axis of the can or receptacle body, whereby the bottom structure is provided with a high side and a low side, with the traction rollers or wheels mounted in assembled relation thereto adjacent to its high side, and so that the low side cooperates with said traction rollers or wheels in providing a stable three point support or base in horizontal plane upon which the can or receptacle stands perpendicular when at rest.

This invention has for a further object to provide a tractional can or receptacle, the inclined bottom structure of which includes a reinforced annular peripheral bottom and can body joint flange dependent from the plane of the underside of the can bottom per se, and by which reinforced flange is carried the axle or journal supporting means for the traction rollers or wheels.

Other objects of this invention, not at this time more particularly enumerated, will be understood from the following detailed description of the same.

Illustrative embodiments of this invention are shown in the accompanying drawing, in which:

Fig. 1 is a side elevation of a refuse can made according to the instant invention, the same being shown in full line representation in its standing position at rest, and by dotted line representation as tipped back for tractional support and movement upon its traction rollers or wheels; Fig. 2 is a fragmentary rear side elevation of the can, viewed in the direction of the arrow X in Fig. 1; Fig. 3 is a fragmentary vertical sectional view, taken on line 3—3 in Fig. 2, but drawn on an enlarged scale; and Fig. 4 is a horizontal sectional view, taken on line 4—4 in Fig. 1.

Fig. 5 is a fragmentary horizontal sectional view through a can body above its bottom, but showing a modified means for mounting its tractional rollers or wheels thereon, said traction rollers or wheels per se being shown in section.

Similar characters of reference are employed

in the above described views, to indicate corresponding parts.

Referring to the drawing, the illustrative embodiment of the tractional refuse can according to this invention therein shown, comprises a body 10 of suitable shape, e. g. of cylindrical shape, having an open top end and a closed bottom end. Said body is preferably made of sheet metal. The upper open end of the body 10 is suitably finished with the usual reenforced beaded edge 11, and said body may be ribbed or fluted or otherwise reenforced in any suitable or well known manner calculated to strengthen the same against battering and distortion.

15 The lower end of the body 10 is so trimmed or shaped that its bottom margins lie in an inclined bottom plane transversely angular to the perpendicular axis of the body. The pitch or inclination of this bottom plane is small, preferably extending at an angle of but two or three degrees relative to a flat plane at right angles to the perpendicular axis of the body. By such construction the rear end of the bottom of the body is spaced above the plane of a supporting surface, while the front end thereof is disposed in the plane of and so as to engage said supporting surface.

20 To the lower end of said body 10 is joined a bottom member 12. This bottom member 12 is provided with a downwardly projecting peripheral flange 13. The lower marginal portions of the body 10, which surround the exterior face of said bottom peripheral flange 13, are preferably provided with inwardly and upwardly turned portions 14 extending around and contiguous to the interior face of said bottom peripheral flange 13, so as to embrace and enclose the latter in manner to provide a closed joint seam formation. Of course, it will be understood that the body 10 and

25 bottom member 12 may be assembled and joined together in any other suitable or well known manner, so long as the resulting bottom structure forms or includes a bottom joint flange dependent from the plane of the inclined bottom member 12, so as to freely project beyond the underside of said bottom member around the periphery thereof. Applied exteriorly around and in engagement with the bottom joint flange, with which the body is thus provided, is a heavy metallic reenforcing band or hoop 15 of substantial width, the lower marginal edges of which extend somewhat beyond the free marginal edges of said bottom joint flange, so as to guard the latter against battering and distortion. Said bottom joint flange and the band or hoop 15 are strongly united and secured together by circumferentially spaced rivets 16 which are riveted therethrough.

30 Extending through the reenforcing band or hoop 15 of the dependent bottom joint flange of the can body, and thus exteriorly beneath the

bottom member 12 of the latter, along a line forming a transverse chord of an arcuate portion of the can bottom at the rear end thereof, is an axle shaft 17, the exteriorly and oppositely projecting ends of which provide journal portions 18 upon which are mounted traction rollers or wheels 19 for the tractional support of said can body. Spacer sleeves 20 are also mounted on said exteriorly projecting journal portions 18 between the band or hoop 15 and the rollers or wheels 19, whereby to suitably offset the latter against contact with the band or hoop likely to impede free rotation thereof. Said rollers or wheels 19 are suitably retained against displacement from said shaft journal portions 18, as e. g. by means of washers 21 and linchpins 22. If desired, the axle shaft 17 may be further supported against displacement, bending or other distortion, by a brace means 23 arranged to embrace a midportion thereof, and which is suitably secured or anchored to an adjacent portion of the bottom joint flange of the can body.

The radius of the traction rollers or wheels 19 is predetermined so that the ground or floor contacting points of their peripheries and the ground or floor contacting point of the can bottom flange at the front end of the can bottom will lie in a common horizontal plane, and thus provide a stable three point support or base in a plane at right angles to the perpendicular axis of the can body upon which the latter stands perpendicular when at rest. It will be observed, that owing to the provision of the but slightly inclined bottom structure of the can body and the novel arrangement and relation of the traction roller or wheel mounting adjacent to the but slightly elevated rear end of said inclined bottom structure, the can body, when either empty or filled, and especially when standing at rest, will possess a low center of gravity, and consequently risk of the can being accidentally overturned, and, if filled, its content spilled, is reduced to a minimum.

It will also be observed that the construction as a whole provides a tractional refuse can of exceedingly simple, compact, and yet sturdy and strong construction, wherein the traction rollers or wheels may be small in size and positioned within the limits of the maximum diameter of the can body, so as to be little likely to impede handling, storage, positioning or other normal uses to which ordinary refuse cans are put.

Affixed to the upper portion of the can body 10, at the rear side thereof at or adjacent to which the traction rollers or wheels 19 are mounted, is a handle means or hand grip member 24, by means of which the can body may be tipped and then pushed or pulled about on said traction rollers or wheels. It will be obvious, that but a limited tipping of the can body for traction is required, in fact a tipping of but a degree or two from the perpendicular is all that is necessary to raise the ground or floor contacting front end of the can bottom structure clear of the ground or floor surface, whereby to tractionally support the can for movement on its rollers or wheels alone. This is indicated by the dotted representation of the can in Fig. 1, which shows its tipped condition for traction.

Another advantage of the low slung position of the traction rollers or wheels in adjacent relation to the but slightly elevated rear end of

the can bottom structure is that accidental back tipping of the can to a degree likely to risk backward overturning thereof will be prevented by contact of the periphery of the rear end of the bottom structure with the ground or floor, and consequently the back tipping movement will be arrested before it results in such shift of the center of gravity as is likely to result in overturning.

10 In Fig. 5 is shown a modified optional arrangement for mounting the traction rollers or wheels 19 in connection with the band or hoop 15 and the bottom flange structure of the can engaged thereby. Instead of employing the previously 15 described through axle shaft, journal brackets 25 may be riveted to the bottom flange and re-enforcing band or hoop structure, said journal brackets having outwardly extending journal members 26 upon which the traction rollers or wheels 19 are rotatably mounted. The axial 20 alignment and projection of the journal brackets and their journal members will correspond to that of the above described axle shaft and its projecting end portions relative to the rear end 25 of the can bottom structure.

I am aware that various changes could be made in the construction and arrangement of the various parts and elements making up the novel tractional refuse can above described without departing from the spirit of this invention within the scope of the appended claims. It is therefore intended that all matter contained in the above description or shown in the accompanying drawing shall be interpreted as illustrative and not in a limiting sense.

35 I claim:

1. A tractional refuse receptacle comprising a perpendicular body open at its top end and having its bottom margins formed to lie in an inclined plane acutely angular to a supporting surface, whereby, when said body stands perpendicular to said supporting surface, the front side of said bottom margin engages said surface while its rear side is spaced somewhat above said surface, a reenforcing band encircling the bottom marginal portions of said body, a flat bottom member having a dependent marginal flange fitted within the open bottom end of said body to close the latter, means to secure said reenforcing 40 band and bottom member flange to the bottom marginal portions of said body, to thereby form a composite annular bottom skirt structure projecting below said bottom member, an axle shaft 45 extending transversely through said bottom skirt structure forwardly adjacent to the rear side of said body, the exteriorly and oppositely projecting end portions of said axle shaft providing traction roller journals, traction rollers mounted on said journals, said rollers being sized 50 to support the body, in conjunction with the supporting surface engaging front side thereof, with its axis substantially perpendicular to the supporting surface, and a handle means affixed to the rear side of said body adjacent to its open 55 top end.

60 2. In a tractional refuse receptacle as defined in claim 1, a brace means affixed to the bottom skirt structure to project inwardly therefrom in supporting connection with the mid-portion of said axle shaft.

70 70 SILVIO M. AITELLI.
